UNITED STATES PATENT OFFICE

ERNEST GREEN, OF LONDON, ENGLAND, ASSIGNOR TO RADIO CORPORATION OF AMERICA, A CORPORATION OF DELAWARE

THERMIONIC GENERATOR

Application filed March 2, 1923, Serial No. 622,415, and in Great Britain March 2, 1922.

This invention relates to thermionic generators or amplifiers of high frequency oscillations and particularly to arrangements for increasing the efficiency of the generators or amplifiers by introducing a conducting shield or screen in proximity to electrodes.

According to this invention a metallic strip or ring placed either inside or outside the bulb is electrically connected to one or 10 other of the valve electrodes. Preferably a small metal ring is arranged at one end of the valve either inside or outside the bulb and is connected to the anode or grid, as the case may be, which is sealed into the opposite end 15 of bulb.

Although not limiting the invention to any particular explanation, such a ring appears to modify the distribution of the electric field produced between the anode, grid and filament electrodes and their leads and supports so that the electric field at the container or envelope is reduced and conduction currents therein or on conducting films on the interior of the container is reduced, whereby the heating 25 of the glass and failure thereof are reduced and the efficiency of the valves is increased.

In cases, however, where the anode and grid are sealed into the same end of the bulb, the 30 supports of one of the electrodes may be so constructed and arranged that they screen the supports of the other electrode and thus reduce the field before mentioned.

My invention is illustrated by the accompanying drawing in which

Fig. 1 illustrates one arrangement in accordance with the invention, and

Figs. 2 to 5 are modifications.

Figure 1 shows a metal ring A surrounding 40 the grid end of the valve and electrically connected to the anode P by the lead B. Figure 2 shows a metal ring C surrounding the anode end of the valve and electrically connected to the grid G by the lead D. Figure 45 3 shows a metal ring E inside the bulb and with its supports F forming a skeleton extension of the anode P. Figure 4 shows the supports p of the anode P screening the supports g of the grid, the anode and grid both 50 being sealed into the same end of the bulb.

In some cases I may employ a ring at each end of the bulb and connected to the electrode which is sealed in at the opposite end.

I find that valves thus constructed have a greater efficiency than like valves unprovided with means for reducing the field above mentioned.

Having described my invention, what I claim is:

1. In a thermionic valve, an enclosure having anode and grid electrodes therein, conducting portions extending from each of said electrodes through opposite portions of the enclosure, and a conducting strip electrically connected to one of said electrodes and surrounding the conducting portions of the other of said electrodes. 60

2. In a thermionic valve, an enclosure having anode and grid electrodes therein, conducting portions extending from each of said electrodes respectively to opposite ends of the enclosure, and a pair of conducting rings, each respectively connected to one of said electrodes and surrounding the extending conducting portions of the other of said electrodes. 70

3. In a thermionic generator, an enclosure having anode and grid electrodes, conducting portions associated therewith and respectively sealed into opposite ends of the container and a conducting member electrically connected to one of said electrodes and surrounding the extending portions of the other electrode. 80
